A. H. PRENZEL

MACHINE FOR MOLDING INSOLE FLANGES

Filed July 9, 1925

UNITED STATES PATENT OFFICE.

ADAM H. PRENZEL, OF HALIFAX, PENNSYLVANIA.

MACHINE FOR MOLDING INSOLE FLANGES.

Application filed July 9, 1925. Serial No. 42,545.

This invention relates to improvements in shoe machinery, and it consists of the constructions, combinations and arrangements herein described and claimed.

5 An object of the invention is to provide a machine for so treating, forming or molding the flange of an insole or other shoe sole that it presents an upstanding but curved relationship to the sole thereby making the 10 flange more readily accessible to the anvil of a lasting machine.

Another object of the invention is to provide means for molding a sole flange into a predetermined shape by a reciprocating 15 motion.

Other objects and advantages appear in the following specification, reference being had to the accompanying drawing, in which—

20 Figure 1 is a side elevation of the molding machine.

Figure 2 is a detail section of the reciprocating plunger, parts being shown in elevation,

25 Figure 3 is a sectional view on an enlarged scale illustrating the action of the hammer in molding the channel flange of a shoe sole.

Figure 4 is a detail sectional view taken 30 substantially on the line 4—4 of Figure 3.

Figure 5 is a detail front elevation of the lower part of the anvil plate.

The herein described machine is for the purpose of carrying out one of the steps of a process in making the insole disclosed in my co-pending application for Letters Patent on molded-flange insole and process of making the same, filed July 9, 1925, Serial Number 42,544. In Figure 3 the insole 1 is 35 peripherally channeled at 2 to produce a flange 3. This flange fits closely to the sole and thus makes the operation of fitting the flange upon the anvil of a lasting machine somewhat uncertain and more or less difficult. It is the purpose of the invention to 40 so mold the flange 3 that it assumes a definite upstanding relationship to the sole, thereby making it easy to run the flange along the lasting machine anvil while staples or other 45 temporary fastening means for such upper structure are inserted.

A frame 4 carries an anvil plate 5 upon a pivotal support 6 for coaction with a hammer 7. The anvil plate has a recess 8 with which the head 9 coacts in giving the flange 55 3 its cross sectionally curved formation. The adjacent surfaces of the recess and hammer head are appropriately curved. The curved surfaces extend across the anvil plate and hammer head respectively. The anvil 60 plate has an opening 10 through which the hammer 7 extends to assume the proper relationship to the anvil plate. The hammer assumes the shape of a hook, but in practice 65 the formation may be otherwise.

Clamping means 11 provide an appropriate mounting for the hammer upon a plunger 12. The plunger is made in two parts and includes the inner section 13. This section is pivotally connected at 14 to the 70 strap 15 of an eccentric 16. Rotation of the shaft 17, upon which the eccentric is mounted, by means of the drive pulley 18 causes rapid reciprocation of the plunger and of the hammer 7 so that the flange 3 is 75 formed or molded as the shoe sole 1 is advanced past the anvil plate 5. This advancement of the insole is facilitated by the revolute table 19 and guide wheel 20. These elements are loosely mounted upon a 80 stud 21. The loose mounting permits limited yielding of the guide wheel 20 in the direction of the axis of the stud so that the shoe sole can be moved past the anvil plate with great freedom. The revolute table 85 and guide wheel act much on the order of a roller bearing for the edge of the shoe sole. The guide wheel is beveled to match the beveled edge of the shoe sole, but in the event of a shoe sole of another shape the 90 guide wheel 20 may be substituted by another of correspondingly appropriate shape.

A slight camber or slope 22 of the upper surface of the table 19 assists in passing the shoe sole 1 through. The reduced and threaded end 23 of the stud extends through a slot 24 in an inclined extension 25 upon which the revolute table and guide wheels are held by a nut 26. The arrangement provides for forward or rearward adjustment 95 of the table and guide wheel in respect to the anvil recess 8 so that an appropriate 100

amount of room can be provided for the edge of the shoe sole. The channel flange 3 may occur farther to the interior of a certain run of shoe soles and in such case it is advisable to adjust the stud 21 to the rear so that there may be room for the sole edge which is more pronounced in this case.

Adjustments of the anvil plate 5 are made by a set screw 27 and fixed by a screw 28. 10 The first merely bears against the back of the anvil plate but the second passes through a slot 29. Upon loosening the lock screw 28 and turning the set screw 27 to the right, the anvil plate 5 is caused to swing upon its 15 pivot 6 so that the recess 8 is brought slightly higher in respect to the hammer head 9 and the concavity in the flange 3 is formed higher or farther toward the feather edge as a result.

20 This adjustment of the anvil plate 5 calls for limited yielding of the hammer 7 when performing a stroke. The range of action of the eccentric 16 is fixed, but a spring 30, interposed between the plunger sections 12 and 13, provides for any necessary yielding of the hammer 7. The plunger 12 has a stem 31 which is smaller in diameter than the bore 32 in the inner section 13. The resulting space houses the spring 30 between 25 a head 33 on the extremity of the stem and a suitable closure 34 at the opposite end of the bore. The closure may be formed either by upsetting the end of the section 13 after the parts are in place or by applying a 30 washer or the like to hold the spring in place.

The operation is readily understood. The shaft 17 upon being driven causes the eccentric 16 to impart a rapid reciprocating motion to the plunger 12 and its inner connected section 13. The plunger has appropriate bearing in the frame 4 and the frame is of such design that it is readily mounted on a suitable support.

40 The hammer 7 reciprocates in front of the anvil plate 5. There is a space between the recess 8 and hammer head 9 and a space between the hammer head 9 and table 19. The channel formed by the combined spaces is intended to receive the flange 3 of a previously channeled and moistened insole 1. The hammering action of the head 9 against the flange 3 is readily started, and the operator has only to move the sole past the anvil 45 plate 5 when the rapid reciprocation of the hammer gives the flange the desired upstanding and curved or concaved formation. The formed or molded flange remains in the position given it by the hammer head, and 50 when dried is ready for other steps in the process of making a shoe.

While the construction and arrangement of the improved insole flange molding machine is that of a generally preferred form, 55 obviously modifications and changes may

be made without departing from the spirit of the invention or the scope of the claims.

I claim:

1. A machine of the character described comprising a table, an anvil providing a support for the table which serves as a guide for a flanged shoe sole while moving across the anvil, and a reciprocating hammer operating against the anvil to mold the flange into a predetermined cross sectional shape. 70

2. A machine of the character described comprising a table, an anvil plate having a recess and an opening, said plate providing a support for the table which serves as a guide for a flanged shoe sole while moving across the anvil, and a reciprocating hammer operating in said opening and being formed into a shape to confront the anvil recess to strike beneath the sole flange and drive it against said recess. 80

3. A machine of the character described comprising a frame, a table, an anvil plate having a flange-forming portion and an opening, said plate supporting the table which guides a flanged shoe sole while moving past the anvil, a hammer reciprocating in said opening being formed into a head to strike beneath the sole flange and press the flange against the flange-forming portion of the anvil to mold the flange into a predetermined cross sectional shape, a plunger by which the hammer is carried and reciprocated, means pivotally mounting the anvil plate upon the frame, and means for adjustably rocking the anvil plate upon its pivot. 90

4. A machine of the character described comprising a frame, a table, an anvil plate having an opening and a recess, a plunger in two sections, means to reciprocate the plunger, a hammer carried by one of the plunger sections and being operable in said opening, means to support a flanged sole during movement said hammer striking beneath the flange of a sole passing across the table pressing it into the recess to mold the flange into a predetermined cross sectional shape, a pivotal mounting for the anvil plate upon the frame, means to adjustably rock said plate upon its mounting to vary the anvil recess in respect to the hammer, and yieldable means interposed between the sections of the plunger permitting corresponding yielding of the hammer in respect to the anvil when necessary. 110

5. The combination of a plunger in two sections, means to reciprocate the plunger, a hammer carried by the plunger said hammer having a head, an anvil plate having a recess opposing the hammer head, means to adjust the anvil plate in a curvilinear direction so that the recess becomes located higher or lower in respect to the hammer and yieldable means interposed between the sections of the plunger permitting correspond- 120

ing yielding of the hammer when required by virtue of the adjustment of the anvil.

6. A machine of the character described comprising an anvil plate having a recess and an extension, a reciprocable hammer having a head driving the flange of a sole against said recess, means by which the sole

is supported and guided, said means including a table with which the bottom of the sole contacts and a wheel against which the edge of the sole runs, and means carried by the extension providing a common revolute mounting for the table and wheel.

ADAM H. PRENZEL.
